ADJUSTABLE BRACKET.

No. 316,459.

Patented Apr. 28, 1885.

UNITED STATES PATENT OFFICE.

WOODBURY STORER HOW, OF CINCINNATI, OHIO, ASSIGNOR TO THE S. S.
WHITE DENTAL MANUFACTURING COMPANY, OF PHILADELPHIA, PA.

ADJUSTABLE BRACKET.

SPECIFICATION forming part of Letters Patent No. 316,459, dated April 28, 1835.

Application filed December 31, 1878.

To all whom it may concern:

Be it known that I, WOODBURY S. HOW, of Cincinnati, in the county of Hamilton and State of Ohio, have invented certain new and 5 useful Improvements in Adjustable Brackets and in the Method of Hanging or Mounting them, of which the following is a specification.

My invention relates more particularly to adjustable brackets of the class in which a table 10 or tray is supported by a frame in a horizontal position, while capable of vertical adjustment in the arc of a circle, (substantially,) the table-carrying frame being jointed to the outer ends 15 of parallel arms, while the inner ends of said arms are jointed to a suitable support.

The objects of my invention more especially are, first, to improve parallel-armed brackets by rendering them capable of more easy operation, and with but little exertion on the part 20 of the operator; second, to provide an improved construction of clamping or locking device at the outer ends of the parallel arms, whereby the table or tray may be conveniently and positively locked at any point in its range 25 of vertical adjustment; third, to provide for the longitudinal extension of the table-supporting arm in a superior manner, so as to avoid the tendency of the extensible arm of the bracket to bind or stick in its socket or support.

30 My object, further, is to improve the construction of brackets so as to render them more useful, and to facilitate the operations of persons—dentists, for example—who may use them.

35 The subject-matter claimed by me herein is first fully described, and then particularly pointed out at the close of the specification.

The accompanying drawings show my improvements as organized in the best way now 40 known to me. It will be understood, of course, however, that changes may be made in the organizations shown without departing from my invention, and that some of my improvements may be used without the others, and in brackets differing from those shown in said drawings, and particularly described herein.

45 In said drawings, Figure 1 is a side elevation of one form of my improved bracket, and Fig. 2 is a similar view from the opposite side 50 thereof. Fig. 3 is a vertical section through

the bracket on the line 3 3 of Fig. 2, showing particularly the construction of the clamp which positively locks the outer ends of the parallel arms, and also the construction of the spring clamp-socket in which the sliding extension-arm of the bracket is carried. Fig. 4 is a section through the bracket on the line 4 4 of Fig. 2, showing particularly the spring clamp-socket of the sliding extension-arm above referred to. Fig. 5 is a view in elevation of a modified form of bracket, showing a different organization of counterbalancing or equipping springs from that shown in Fig. 1, also a modified form of clamp for the parallel arms, and also a different form of seat 65 for the sliding extension-arm which carries the table or tray; and Fig. 6 is a section therethrough on the line 6 6 of Fig. 5. Fig. 7 is a view in elevation of still another modification of my improvements, the equipping or counterbalancing of the load at the outer ends of the parallel arms being effected by an adjustable weight instead of by a disposition of a spring or springs, as shown in Figs. 1, 2, and 5; and Fig. 8 is a view in elevation, partly in 70 section, of a simple form of bracket unprovided with the parallel arms, but having the same description of seat for the sliding extension-arm as that shown in Fig. 5.

In the organization of the brackets shown 80 in the drawings a crane-plate, A, is pivoted to the wall or some other support, so as to be capable of turning horizontally, the connection being formed in the examples illustrated in all instances, save in Fig. 7, by vertical 85 pivots *a a'* of the crane-plate fitting suitable seats or sockets in projecting lugs or supports *b b'*, attached to the wall B, for instance. I prefer the lower lug, *b'*, to be provided with a tapering seat or socket for the lower tapering journal or pivot, *a'*, of the crane-plate A, 90 whereby, owing to the large frictional surface of the lower pivot, the crane-plate will have a tendency to remain stationary when adjusted, and will require more power to move it on 95 its pivots than if both pivots or journals of the crane-plate were plain or straight pivots. This is important in that it conduces to a bracket the movements of which are steady and solid.

Parallel arms C C are pin-jointed at their inner ends to the crane-plate A, while their outer ends are similarly jointed to one side of the frame D, which I will call a "horizontal" 5 frame, inasmuch as it remains horizontal or in a constant plane notwithstanding vertical adjustment in a curved path. This horizontal frame in the present instance consists of a flat plate carrying in Figs. 1, 2, 3, 4, 5, and 6 10 a box or seat for the reception of a longitudinally-extensible arm, E, carrying at its outer end the table or tray of the bracket. In Fig. 7 the horizontal frame D is provided with a fixed arm, upon which the table or tray is 15 mounted. The same pivots which unite the outer ends of the parallel arms to the horizontal frame also pass through a link-clamping plate, F, fitted on the opposite side of said arms in such manner that said plates D and 20 F are loosely united by said pivot-pins with the ends of the parallel arms between them, and said arms are loosely jointed to said plates.

In order to positively clamp the horizontal frame-plate D and clamp-plate F together and 25 to the outer ends of the parallel arms C C, so as to lock said arms and the horizontal frame at any point desired in their range of vertical movement, whereby to sustain the arms in a fixed position, I pass a clamp-screw, e, through 30 said plates D F, and preferably between the outer ends of the parallel arms in the organizations shown in Figs. 1, 2, and 3, whereby, by tightening a clamp-nut, e', upon the threaded part of said screw, the plates D F are tight- 35 ened upon the ends of the arms C C or are loosened by the reverse movement of said nut, as the case may be, whereby a ready means is afforded for clamping or releasing both the parallel arms by a single clamp, 40 which in its effective action and convenience is much superior to, for instance, clamping the arms each by a separate clamp or device, which I desire here to acknowledge to be old and not of my invention, or of clamping both 45 arms to the horizontal frame by a curved slotted plate and thumb-nut, which I also here acknowledge to be old.

In the construction of bracket shown in Figs. 5, 6, and 7 the locking-clamp is formed by 50 making one of the pivots of the outer ends of the parallel arms in the form of a set-screw having a handle at one end, while the screw-threaded shank passes through the clamp-plate F and parallel arm and into a female 55 thread in the horizontal frame-plate D. By tightening or loosening this screw the end of the parallel arm will be clamped between the frame D and plate F, or be released, as the case may be.

60 In place of or in addition to either form of the screw-clamp lock I have described, an automatic detent device may be employed to lock the parallel arms in their vertically-adjusted position as against descending movement, and 65 it preferably consists of a series of ratchet-teeth, d, formed on the inner edge of the horizontal frame-plate D, for instance, with which

the point of the pawl P, pivoted on one of the arms C, engages, as clearly shown in Fig. 2. This pawl is weighted at its lower end to automatically engage its upper locking end with the ratchet-teeth d, and the weighted end is shaped so as to constitute the lower end of the pawl a convenient handle by which to operate it to disengage its upper end from the ratchet-teeth when the table is to be adjusted. As soon as released the pawl automatically engages the ratchet.

The horizontal frame-plate D in the organization shown in Figs. 1, 2, 3, and 4 carries a 80 spring leaf or portion, d', bent so as to form a tubular seat or recess for the reception of the extension-arm E, which may be moved freely endwise in said seat when expanded, in order to extend or contract the length of the 85 bracket. This extension-arm is preferably hollow for lightness, and is also preferably provided with a flat side next the frame-plate D, instead of being circular in cross-section, whereby the extension-arm, while capable of 90 being moved freely endwise, cannot turn in its seat. When unrestrained, the tendency of the tubular clamp is to separate or expand, so as to enlarge the seat of the extension-arm E, and thus permit said extension-arm to be 95 moved or adjusted endwise with great freedom and without the binding or sticking action to which the similar arms of all brackets heretofore constructed of which I am aware are liable.

In order to contract the clamp so as to lock the extension-arm in any position to which it may be adjusted, I have provided the horizontal frame-plate D with a set-screw, the threaded end of which is extended through 105 the extension or flap d' of the spring-clamp into the frame-plate D, whereby by tightening the said screw the tubular seat of the clamp is contracted and caused to bind throughout its length upon the extension-arm, so as to 110 lock it securely in its adjusted position. By loosening said screw the clamp expands to permit free endwise movement of the extension-arm, as before explained.

The outer end of said extension-arm E carries the table or tray G of the bracket, which may be of any approved construction, or such as those in common use suitable for the purpose. I prefer that the table or tray be mounted on the extensible bracket-arm so as to be 120 capable of being turned freely horizontally on said arm; and instead of the plain ordinary pivotal connection usually employed for this purpose, I prefer that the pivot be tapered, so as to increase the frictional surface and cause 125 the table to remain fixed unless positively turned. In some instances the extensible arm E, instead of being adjustable in a tubular spring-clamp such as I have shown and described, may be adjustable in a box carried 130 by the horizontal frame, which is lined or packed with a dry non-metallic anti-friction substance—such as wood or leather—which permits free endwise movement of said

extensible arm without binding or sticking in its seat. A box or casing lined or provided with a non-metallic bushing is shown in Figs. 5, 6, and 8.

5 In Fig. 8 the extensible arm E is fitted to slide in a seat in an arm connected directly with the crane-plate or to the wall, and without the intervention of the parallel arms which afford vertical adjustment.

10 In some instances the table or tray will be mounted directly upon or be carried by the horizontal frame D, and not by said frame through the medium of an extensible arm. In other words, in some instances the extensible 15 arm fitted on the bracket may be dispensed with—as in Fig. 7, for example. In the form of bracket shown in said figure the crane-plate A is pivoted to the outer end of the swinging or folding arm H, which permits of 20 extending the table or tray more or less from the wall or support of the bracket.

In order to render the bracket vertically adjustable with ease and with but little exertion on the part of the operator, I have, after long 25 study and repeated experiment, devised a method of and means for counterbalancing the weight of the pivoted bracket-arms and table so that the parallel arms and table at their outer ends are in equipoise, and will remain in 30 the position vertically to which they are moved without the aid of locking or clamping devices. It will thus be seen that in moving the table up or down but slight effort is required, there being practically no weight either 35 to lift when moving the table upward or to sustain when adjusting the table to a lower position. When adjusted, a clamping or locking device may, if desired, be operated to positively fix the table in its adjusted position. 40 This arrangement for preserving the equipoise of the arms and table in their limited vertical range of movement may consist either of a spring or springs or of a weight, the organizations of which I will now particularly describe.

45 In Figs. 1 and 2 I have shown two springs, I I', connected to the crane-plate and one to each of the parallel arms C C'. The lower spring, I, is a coil-spring connected at its outer end to the lowermost of the parallel arms, at or about the center of said arm, by means of a hooked pin, i, and at its inner end to the crane-plate by a similar hooked pin, i'; at a point a short distance above the pivotal point 50 of the arm upon the crane-plate, as clearly shown in Figs. 1 and 2. With the spring lying in nearly the same line as the arm with which it is connected, as shown, said spring has the effect of keeping the arm and table in 55 equipoise, its action being such that its tension or power increases or decreases in proportion to the increase or decrease of leverage of the parallel arm within its range of movement upon its pivotal connection with the crane-plate A, which range of movement is limited by contact of the parallel arms or of suitable stops thereof.

The line of action of the coil-spring may be varied within certain limits, while still substantially retaining the equipoise of the parts; 70 but a wide departure from the organization shown radically changes the action of the spring, and while up to a certain point it may act to sustain the weight of the arms and table, still above that point it will not sustain the 75 load, and if the table be carried below the point of sustentation by force and then released the spring will react and draw or throw the table quickly back. An example of such an organization of a spring with a parallel-armed 80 bracket is shown in the *Dental Advertiser* (volume 8) for 1877, page 111; but such an arrangement is radically different from the organization devised by me. In one case the spring is a reacting or returning spring to sustain a part of the weight of the arms and its 85 table-load, while in my case an equipoise of the arms and load throughout their range of movement is effected. It is suggested in the form of device shown in the *Advertiser*, above 90 alluded to, that, owing to the size and number of the bearings, (joints or pivots,) a moderate degree of tightness, in connection with the spring, will render the bracket self-sustaining without recourse to clamping devices or ratchets. In my invention the parallel arms are 95 loosely pivoted, and the spring or weight alone affects the equipoising of the bracket, whereby the adjustment of the bracket is very easy, which is not the case with the bracket shown 100 in the *Advertiser*, where the friction of tightened joints has to be overcome in adjusting the bracket. It was to avoid this very thing that my improvements in this direction were devised.

The equipoise coil-spring may be duplicated—that is, an additional spring of the same character may be similarly connected to the uppermost of the parallel arms, as shown in Fig. 5. These springs are adjustable in this 110 instance at their inner ends by means of their connecting-pins i', which are fitted for insertion in any one of a series of holes, i'', in the crane-plate, the line of holes preferably being in the arc of a circle, as clearly shown in Fig. 115 5. It will be understood, however, that various other ways of adjusting the springs may be employed without departing from my invention, some of which will be obvious to skilled mechanics. This adjustability of the 120 spring is to compensate variations in the load which the table or tray is designed to carry.

Instead of duplicate springs, only one spring may be used, and that may be an arm or lever spring, as clearly shown in Figs. 1 and 2. This 125 spring is fitted to and coiled at its inner end around a stud or post on the crane-plate, while its lever-arm is passed under a hook or projection on one of the parallel arms at or about its center. The organization is such that any 130 downward movement of the parallel arms from the extreme limit of their upward movement causes the hook or projection to move endwise on the spring-arm, and also to bend said arm

and increase the resistance of the spring as the leverage of the arm is increased by being moved downward, thereby exactly preserving the equipoise of the parallel arm and the table carried by it, whereby the same effect is produced as by the use of the spiral spring or springs before described—to wit, the weight of the table is in equipoise, and will remain in the vertical position to which it may be moved 10 without the aid of fastening devices or other contrivance.

Instead of springs such as I have described, a weight may be employed, as clearly shown in Fig. 7. In this modification the upper parallel arm is carried back beyond its rear pivotal connection with the crane-plate A, and the weight is mounted on the inner end of said extended arm. Said weight is adjustable by means of the row of holes, for example, for the 20 same purpose as the spiral springs before described, and the action in maintaining the equipoise of the bracket-arms and table is substantially the same.

I do not claim in this application the specific arrangement of the weight for maintaining the equipoise of the bracket, nor mounting the parallel arms by their turning-crane connection upon a folding arm, nor the lined or bushed box or casing in which the extensible arm E is fitted, nor the automatic locking device herein described. These parts or features of my invention will be embodied in a division of this application to be filed.

I claim as my invention—

35 1. The combination, substantially as hereinbefore set forth, of the crane-plate, the loosely-pivoted vertically-adjustable parallel arms, and an equipoising device, substantially as described, whereby said arms are maintained in

equipoise at different points in the range of 40 their adjustment and the object carried by the parallel arms readily and easily elevated and lowered and left at the desired point without the aid of clamps, ratchets, or tightening devices.

2. The combination, substantially as hereinbefore set forth, of the crane-plate, the pivoted vertically-adjustable parallel arms, a device, substantially as described, by which said arms are maintained in equipoise at different 45 points in the range of their adjustment, and adjustable connections for said equipoise device whereby variations in weight at the outer ends of the parallel arms may be compensated.

3. The combination, substantially as hereinbefore set forth, of the pivoted parallel arms, the horizontal frame jointed to one side of the outer ends of said arms, the clamp-plate jointed to the other side of said outer ends of said arms, and by the same pivots that joint the 50 parallel arms and horizontal frame together, and a clamp-screw passing through said horizontal frame and said clamp-plate.

4. The combination, substantially as hereinbefore set forth, of the horizontal frame at 55 the outer ends of the pivoted parallel arms, an expansible and contractible spring socket or box carried by said frame, and an extension-rod fitted to move endwise in said socket when expanded, and be locked at the point desired 70 by contracting said socket.

In testimony that I claim the foregoing as my own I affix my signature in presence of two witnesses.
